CLAIM

(57) The ornamental design for a display screen for digital camera, as shown and described.

DESCRIPTION

FIG. 1 illustrates a display screen of a digital camera, showing my new design, in which a taking lens is in an in-focus state; and, FIG. 2 illustrates the display screen of the digital camera in use, in which the taking lens is in an in-focus state. The portions of the display screen for digital camera in broken lines are shown for illustrative purposes only and form no part of the claimed design.
